UNITED STATES PATENT OFFICE.

BENJAMIN GARVIN, OF INDIANAPOLIS, INDIANA, ASSIGNOR TO AMERICAN SANITARY
LOCK COMPANY, OF INDIANAPOLIS, INDIANA, A CORPORATION.

COIN-CONTROLLED LOCK.

1,132,467.

Specification of Letters Patent. Patented Mar. 16, 1915.

Application filed September 9, 1912. Serial No. 719,832.

To all whom it may concern:

Be it known that I, BENJAMIN GARVIN, a citizen of the United States, residing at Indianapolis, in the county of Marion and

5 State of Indiana, have invented a new and useful Coin-Controlled Lock, of which the following is a specification.

It is the object of my invention to provide a coin-controlled lock which can be 10 operated from one side only by depositing a coin but can be operated from the other side without a coin; which makes a record of its coin-produced operations; which after having once been operated by a coin cannot 15 again be similarly operated until after it has been operated from the other side; which is as thin as possible, even thinner than the diameter of the coin; and which is substantially fool-proof and is without ex- 20 posed parts which can be tampered with.

The accompanying drawing illustrates my invention.

Figure 1 is a front elevation of the complete lock, with some parts broken away; 25 Fig. 2 is a front elevation of such lock with the cover removed, but with the operating member carried by such cover shown in place; Fig. 3 is a view similar to Fig. 2, but showing the bolt drawn back; and Fig. 30 4 is a section on the line 4-4 of Fig. 2.

The base 10 of the lock may be fastened on the door 11 by screws 12, which are covered when the cover 13 of the lock is in place. A bolt 14 is mounted in a suitable 35 guideway 15 in the base 10, and is spring-pressed outwardly by a spring 16. The bolt 14 is provided with a shoulder 17 at its inner end, which shoulder is suitably spaced from the arm 18 of an operating lever 19 40 overlying the bolt so that there is just space for the desired coin, usually a five cent piece, to be received edgewise between such shoulder and arm. The coin may be dropped in from the outside of the door through a horizontal slot 20 in the front face of the cover 45 13, passing thence by gravity through a coin chute 21 located within the casing formed by the base 10 and cover 13 and having a suitably curved back to guide the coin 50 into the space between the arm 18 and shoulder 17, and bolt 14 and cover 13. If now the operating lever 19 be turned by the knob 22 on the front of the lock, the shank 23 of which knob is attached to the operating 55 lever 19 by a screw 24 within the lock cas-

ing, the arm 18 pushes the coin edgewise, and through the coin and the shoulder 17 withdraws the bolt 14 to permit the door to be opened. At the same time, a projection 25 from the lower end of the operating lever 60 19 passes upward into a notch 26 in the lower side of the bolt 14, and also pushes upward a slide 27 from the position shown in Fig. 2 to the position shown in Fig. 3. The projection 25, after once entering the 65 notch 26 will prevent the bolt 14 from being pushed out by the spring 16 if the coin for any reason should drop from between the arm 18 and shoulder 17, thereby preventing the user from losing his coin by inexpert 70 manipulation of the lock. Moreover, the projection 25, acting against the under surface of the bolt 14, prevents the knob 22 from being turned at all unless there is a coin between the arm 18 and the shoulder 17. 75

The upward movement of the slide 27 operates a register 30, the arm 31 of such register fitting in a notch 32 in the slide 27. The slide 27 is provided with a transverse arm 33 which when the slide moves 80 upward covers the inner side of the slot 20, as indicated in Fig. 3. This prevents another coin from being dropped in the slot while the slide is in this position.

When the user releases the knob 22, the 85 spring 35 pushes it back to normal position, and at the same time the spring 16 pushes the bolt 14 to its normal position. During this time, the coin remains held, under ordinary conditions, between the arm 18 and 90 the shoulder 17, a shoulder 36 on such arm preventing the coin from dropping. This also helps to prevent loss of the coin by inexpert manipulation of the door. As the door is now closed, the bolt 14 is momentarily pushed inward by the usual cam action of the bolt on the door frame, and the coin is released and drops down into the bottom of the lock casing. When the user 95 now desires to open the door from the inside, he turns the inside knob 40, the shank 41 of which carries an operating lever 42 fastened to such shank by a screw 43 within the lock casing. The lever 42 has two fingers 44 and 45, the former coöperating with 100 a notch 46 in the upper surface of the bolt 14 to slide such bolt inwardly, and the latter coöperating with a shoulder 47 on the slide 27 to move said slide back from the position shown in Fig. 3 to the position shown 110

in Fig. 2, thereby returning the register arm 31 to the position from which it may again operate the register and also moving the transverse arm 33 of the slide from its 5 position covering the slot 20. As the knob 40 is now released, the spring 16 returns the bolt 4 to its normal outward position, and the lock is again ready for operation by a coin.

10 In order to allow the lock to be opened from the outside by an authorized person, the cover 13 is provided with a key hole 50, whereby a porter's key may be inserted in the hole 51 for the key shank and the wards 15 of the key may coöperate with a notch 52 on the upper surface of the bolt 4 to withdraw such bolt. This withdrawal of the bolt does not affect the slide 27. When the lock is operated by the porter's key, the wards of the 20 latter, as the turning thereof is completed, enter a notch 53 on the edge of the slide 27, thus locking such slide and the knob 22 against movement.

25 The cover 13 of the lock is provided with a removable panel 55 provided with a lock 56. By unlocking the lock 56 and removing the panel 55, the coins which have collected within the lock casing can be removed. Beneath the panel 55, the cover 13 is provided 30 with a pair of lugs 57, through which screws 58 extend into the holes 59 in the base 10 of the lock. These screws hold the cover 13 upon the base, and are covered when the panel 55 is in place. Since the screws 58, 35 the screws 12, and the screws 24 and 43 are all inaccessible when the lock is in working

condition, it is practically impossible for the lock to be tampered with.

I claim as my invention:

1. The combination, in a coin-controlled lock, of a casing, a bolt slidably mounted therein and provided with a shoulder and a notch, an operating lever which may act to withdraw such bolt when a coin of the required denomination is deposited between 45 the lever and said shoulder, and a projection on said operating lever which swings into the notch in the bolt when the bolt is withdrawn but which bears against a side of the bolt and prevents the turning of the 50 operating lever unless the required coin is deposited.

2. The combination, in a coin-controlled lock, of a casing, a bolt slidably mounted therein, and provided with a notch, an operating lever which when a coin of the required denomination is deposited may act through said coin to withdraw the bolt, and a projection on said operating lever which swings into the notch in the bolt when the 60 belt is withdrawn but which bears against a side of the bolt and prevents the turning of the operating lever unless the required coin is deposited.

In witness whereof, I have hereunto set 65 my hand and seal at Indianapolis, Indiana, this 6th day of September, A. D. one thousand nine hundred and twelve.

BENJAMIN GARVIN. [L. s.]
